United States Patent [19]

Bar**Patent Number: Des. 415,567****Date of Patent: ** Oct. 19, 1999**

[54] **DISPLAY ELEMENT OF BIOMEDICAL APPARATUS FOR MEASURING OR EVALUATING PHYSICAL VARIABLES**

[75] Inventor: **Christopher A. Bar**, Belleville, Ill.

[73] Assignee: **Roho, Inc.**, Belleville, Ill.

[**] Term: **14 Years**

[21] Appl. No.: **29/093,869**

[22] Filed: **Sep. 21, 1998**

[51] LOC (6) Cl. **24-01**

[52] U.S. Cl. **D24/165**

CLAIM

The ornamental design for display element of biomedical apparatus for measuring or evaluating physical variables, as shown.

DESCRIPTION

FIG. 1 is a front perspective view of the invention;
FIG. 2 is a front elevational view of the invention;
FIG. 3 is a rear elevational view;
FIG. 4 is a left side elevational view;
FIG. 5 is a right elevational view;
FIG. 6 is a top plan view; and,
FIG. 7 is a bottom view.
